UNITED STATES PATENT OFFICE.

JOHN G. BLESSING, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

IMPULSE-TRANSMITTING DEVICE.

Application filed March 15, 1924. Serial No. 699,423.

The present invention relates in general to impulse transmitting devices of the dial type commonly used at substations of automatic telephone systems; and the object of 5 the invention is to produce an improved mechanism of the above character embodying a number of novel features tending to increase its efficiency and simplicity, thereby enhancing its usefulness in practice.

10 The invention is illustrated in the accompanying drawing comprising Figs. 1 to 5, inclusive, which are briefly described below.

Fig. 1 is a front view of the complete calling device.

15 Fig. 2 is a rear view showing the various parts in their normal position.

Fig. 3 is a view of certain parts of Fig. 2 when in an off normal or impulse transmitting position.

20 Fig. 4 is a side view of Fig. 3.

Fig. 5 is an enlarged cross sectional view of one of the parts shown in Figs. 2, 3, and 4.

25 Since none of the novel features in the present invention have to do with the gear train used the details of this part of the calling device have not been shown. It may be advisable, however, to briefly point out that the calling device is provided with the usual pawl and ratchet mechanism between the finger hole dial and the gear and impulse transmitting mechanism. Furthermore, the device is of the type in which the shaft acting as a support for the finger hole dial extends beyond the rear of the device. A calling device of this general character is disclosed in Patent No. 1,279,352, issued to A. E. Keith September 17, 1918.

30 It is a well known fact that a calling device of this character is preferably arranged to create a prolonged time interval between the transmission of the final impulse of one digit and the transmission of the first impulse of the succeeding digit. This feature is desirable in that it permits a greater time for automatic operation of switches following a directive movement thereof previously effected by impulses transmitted by the calling device. In order to accomplish the 35 above result in the present case a very simple arrangement is employed.

Referring to Figs. 1 and 2 of the drawings, the dial 1 is fixed to one end of a shaft 3 and on the opposite end of this shaft is fixed a member having arms 4 and 5. A 55 metal pin 6 is carried by member 4 but is insulated therefrom as shown in Fig. 5.

The usual impulse and shunt springs are mounted on a bracket 7 and are insulated therefrom in the usual manner. 60

Impulse springs 8 and 9 are provided with downwardly extending ears 13 and 14, respectively. Shunt spring 12 is provided with a pin which extends through holes in shunt springs 11 and 10, respectively. The 65 holes in these latter springs are amply large and in no case does the pin 15 come into contact with either of these springs. The tension of spring 12 is such that it always tends to engage spring 11. This, however, 70 is normally prevented by the bushing 16 on impulse spring 9 engaging pin 15, the spring 9 being normally held in this position by pin 6.

It will be noted that the springs of the 75 above described spring assembly are mounted with their wide surfaces at right angles to the base of the calling device. This is desirable in that it permits adjustment of the springs to be more readily made, and 80 is accomplished by providing a new and improved type of impulse cam 17 made in the form of a cup with certain parts of the wall cut away.

The large space between the first finger 85 hole on the dial and the finger stop is ample to bring about one complete revolution of cam 17 or a sufficient distance to, ordinarily, transmit two impulses when the digit "one" is dialled. When the digit "two" is dialled 90 the distance of displacement is sufficient to cause the gear train to operate the cam one and one-half revolution or a sufficient distance to, ordinarily, transmit three impulses. The last half revolution is, however, rendered 95 ineffective in a manner which will now be described.

In order to make clear the manner of accomplishing the above described result it will be assumed that the digit one is dialled. 100 The operator inserts a finger in the first hole, designated "1", and rotates the dial

in a forward direction. As soon as the dial is rotated a sufficient distance to ordinarily transmit one impulse if allowed to return to normal, arm 4 moves pin 6 out of engagement with ears 13 and 14, thereby permitting the contacts of impulse springs 8 and 9 to be substituted for pin 6 and ears 13 and 14. The slight movement of impulse springs 8 and 9 also brings these springs into range of the impulse cam so that any rotation of the cam while pin 6 is disengaged from springs 8 and 9 will be effective. Also due to the slight movement of spring 9 away from pin 15 springs 10, 11, and 12 come into engagement with each other under tension of spring 12.

At the commencement of forward rotation of the dial, arm 5 also moves out of range of governor stop 18 so that the cam 17 may be rotated.

As soon as the operator has rotated the dial until his finger engages stop 19, arms 4 and 5 are carried still farther away from the parts affected thereby. Fig. 3 shows the position of arms 4 and 5 when the dial has been rotated from the finger hole designated "1". The operator now removes his finger from the finger hole and allows the dial to return to normal under control of the usual power spring and governor, effecting the operation of the impulse gear train in the usual manner. The impulse cam on its first half rotation operates the impulse springs once, transmitting one impulse, but just prior to the next, last, half rotation pin 6 again engages ears 13 and 14 again short circuiting springs 8 and 9 and moving these springs out of range of the impulse cam, and in addition through the medium of bushing 16 on spring 9 and pin 15, again brings about the disengagement of springs 10, 11, and 12. Just prior to the final portion of rotation of cam 17 arm 5 again moves into the path of stop 18, thereby preventing any over run of the impulse cam.

From the above description it will be evident that without adding any complicated mechanisms, applicant has devised a very simple and positive means for causing a delay at the end of an impulse series, and has also utilized this same means for operating a set of auxiliary or shunt springs.

What is therefore considered new and is desired to have covered in Letters Patent will be brought out in the appended claims.

What is claimed is:

1. In an impulse transmitting device of the dial type, impulse springs, a cam for operating said springs in opposite directions, and means for moving said springs out of range of the cam while maintaining them in electrical contact during a certain operation of said cam,

2. In an impulse transmitting device, a pair of impulse springs, a rotatable cam, means for rotating said cam to effect interruptions of current flow through said springs by separating them, and additional means for separating said springs while maintaining them electrically connected, thereby rendering an operation of said cam ineffective.

3. In an impulse transmitting device, a rotatable cam comprising a disk of insulating material having cam surfaces extending upward at right angles to the disk, and impulse springs having their wide surfaces lying in planes at right angles to said disk and positioned in operative relation to said cam surfaces.

4. In a calling device, a pair of impulse springs, a non-conducting cam for momentarily separating said springs a plurality of times when the device is operated, and a conducting cam for separating said springs to render the operation of said first cam electrically ineffective.

5. In a calling device, a pair of impulse springs, a non-conducting cam for momentarily separating said springs a plurality of times when the device is operated, a conducting cam normally holding said springs apart and out of range of said first cam, and means for withdrawing said second cam during the operation of said first cam.

6. In a calling device, a pair of springs having cooperating impulse transmitting contact points, and a conducting member normally wedged between said springs to hold said contact points apart while maintaining said springs electrically connected.

7. In a calling device, a dial rotatable forward and back, impulse springs, a cam co-operating with said springs and operated by the dial during both movements thereof, and a second cam for directly operating each of said springs operated by said dial only during the return movement thereof.

8. In a calling device, a dial rotatable forward and back, a shaft supporting said dial, a pair of impulse springs, an impulse cam operated during the return movement of the dial to separate said springs a plurality of times, and a member fixed to said shaft and operated thereby to separate said springs before the return of the dial is completed.

9. In a calling device, a dial rotatable forward and back, a shaft supporting said dial, a pair of impulse springs, an impulse cam operated during the return movement of the dial to separate said springs a plurality of times, and a member fixed to said shaft and operated thereby to separate said springs before the return of the dial is completed, said member being of conducting material

whereby the said springs are maintained electrically connected although physically separated.

10. In a calling device, a pair of impulse springs, a non-conducting cam for momentarily separating said springs a plurality of times when the device is operated, a conducting cam normally holding said springs

apart and out of range of said first cam, and means for withdrawing said second cam 10 during a certain operation of said first cam.

In witness whereof, I hereunto subscribe my name this 12th day of March, A. D., 1924.

JOHN G. BLESSING.
